UNITED STATES PATENT OFFICE

95,050

DESIGN FOR A SHOE

David Levin, New York, N. Y., assignor to D. Armstrong & Company, Inc., Rochester, N. Y., a corporation of Massachusetts

Application January 4, 1935, Serial No. 54,718

Term of patent 3½ years

To all whom it may concern:

Be it known that I, David Levin, a citizen of the United States, residing at New York, in the county of New York and State of New York, have invented a new, original, and ornamental Design for a Shoe, of which the following is a specification, reference being had to the accompanying drawing, forming part thereof.

In the drawing:

Figure 1 is a top plan of a shoe showing my new design; and

Figure 2 is a side elevation of the same. Both

sides of the shoe present substantially the same appearance.

The essential feature of the invention resides in the ornamentation of the material of which the shoe is made. As the design is applicable to shoes of various shapes and styles the representation of shoe is merely conventional, for showing an application of the design.

I claim:

The ornamental design for a shoe, as shown and described.

DAVID LEVIN.
